(57) **CLAIM**

The ornamental design for a micro flow channel chip, as shown and described.

DESCRIPTION

FIG. 1 is a top plan view of a micro flow channel chip showing our new design, a bottom plan view thereof being a mirror image;

FIG. 2 is a front elevational view thereof, a rear elevational view being a mirror image;

FIG. 3 is a right side elevational view thereof, a left side elevational view being a mirror image;

FIG. 4 is a partially enlarged top plan view thereof showing the claimed portion of FIG. 1, a partially enlarged bottom plan view thereof being a mirror image;

FIG. 5 is a partially enlarged front elevational view thereof showing the claimed portion of FIG. 2, a partially enlarged rear elevational view thereof being a mirror image; and,

FIG. 6 is a partially enlarged right side elevational view thereof showing the claimed portion of FIG. 3, a partially enlarged left side elevational view thereof being a mirror image.

The broken lines illustrating the unclaimed portions of the micro flow channel chip form no part of claimed design.

1 Claim, 3 Drawing Sheets
